CARRIAGE CUSHIONING MEANS FOR
CALCULATING MACHINES

Ingermar Lundquist, East Orange, N. J., assignor to Monroe Calculating Machine Company, Orange, N. J., a corporation of Delaware

Application August 8, 1952, Serial No. 303,267

2 Claims. (Cl. 235—63)

The invention relates to carriage shifting mechanism for calculating machines and more particularly to improvements in carriage shifting mechanism of the type disclosed in Patent No. 2,473,471 issued on June 14, 1949, to Herman Gang. This type of shift mechanism is adapted to raise a pivotally mounted carriage to disengage the register transmission gears in the carriage from those in the fixed frame of the machine to thereby permit denominational shift of the carriage. The arrangement is such that the carriage is raised during the first half step of a denominational shifting operation, and during the second half step of the operation, gravity assisted by a pair of locators moves the carriage downwardly to reengage the register transmission gears. Normally, the downward movement of the carriage would be accelerated and considerable objectionable noise would result from sudden arrest of the movement at the completion of the shifting operation. To minimize this noise, the aforesaid patent discloses a cushioning arrangement comprising a governor which retards the downward movement of the carriage. The governor, however, is effective throughout substantially the entire downward movement of the carriage and this has been found to slow the shifting operation.

The present invention provides carriage cushioning means which is substantially ineffective to control the downward movement of the carriage until near the end of such movement in a shifting operation effected by mechanism of the type referred to above. The devices of the invention prevent acceleration near the end of the downward movement of the carriage and therefore do not substantially reduce the speed of the shifting operation while appreciably reducing the noise attendant therewith. The invention, however, will best be understood from the following description with reference to the accompanying drawings in which:

Fig. 1 is a vertical section through the machine embodying the invention with the parts in normal position.

Fig. 2 is a detail fragmentary view taken on the line 2—2 of Fig. 1.

Fig. 3 is a fragmentary vertical section showing parts of the invention shown in Fig. 1 in an operated position.

The carriage 1 is provided at its rear with a shaft 3 extending between the end plates thereof and slidably and rotatably mounted in the side frames of the machine. The carriage is therefore adapted to be raised at its forward edge to disengage the gears 5 of the wheels 7 of the product dividend register from the transmission gears 9 so that the carriage may be longitudinally shifted. The transmission gears 9 which are mounted in the body of the machine are driven by digital and tens carry actuating mechanism (not shown) as is well known in the art.

As fully disclosed in the aforesaid patent, carriage 1 is denominational shifted upon a 180° turn of a shaft 11 which is journaled in suitable bearings beneath the keyboard of the machine. Shaft 11 may be manually rotated by a handle 12 (Fig. 1) or may be rotated auto-

2

matically as described in the above-noted patent to which reference is made for such operation.

The means whereby carriage 1 is shifted upon rotation of shaft 11 includes a double arm crank 13 mounted at the rear end of the shaft and provided with a pair of diametrically disposed rollers 13'. The rollers 13' are equidistantly spaced from shaft 11, and when the carriage is in its normal lowered position, the rollers lie in a horizontal plane (Figs. 1 and 2) and respectively engage a scalloped recess 15 in the lower edge of a rail 17 at the forward edge of the carriage. Rollers 13', therefore, act to support the forward edge of the carriage when it is in its normal lowered position.

Crank 13 is rotated a half turn clockwise (Fig. 2) to effect a right shift of one order and counterclockwise to effect a left shift. When crank arm 13 is rotated clockwise, for example, the leftmost roller 13' in engagement with a recess 15 will, through the first 90° of travel, raise the carriage pivotally and at the same time move it toward the right. During this movement, the rightmost roller 13' of crank arm 13 will be moved downwardly from engagement with its recess in rail 17 as the forward edge of the carriage is moved upwardly. When crank 13 has passed the 90° point, no further application of power to shaft 11 is necessary to complete the shift, as the weight of the carriage assisted by a pair of locators, to be described, will urge said crank further in clockwise direction to complete the half turn as the carriage moves downwardly and to the right into shifted position.

Each locator comprises a lever 19 fulcrumed to the inner side of the left and right side frames of the machine respectively. Each lever 19 is urged clockwise by a spring 19' and has pivoted at its rearward end an upwardly standing arm 21, which at its upper end has a U-shaped jaw 21' embracing carriage rail 17 and through which said rail is longitudinally slidably in the shifting of the carriage. Therefore, as carriage 1 moves downwardly in the shifting operation, the locators comprising levers 19 and arms 21 will insure the completion of such movement and of the carriage shift operation. As disclosed in the aforesaid patent, the levers 19 are moved against fixed stops at the conclusion of a shifting operation. The engagement of levers 19 with these stops and the engagement of the disengaged roller 13' of crank 13 with a recess 15 at the conclusion of a shifting operation result in the objectionable noise heretofore noted.

The cushioning means of the present invention for controlling downward movement of the carriage comprises a pair of control trains of similar construction and operation including each pair of levers 19 and arms 21 respectively. Therefore, only one of the control trains and its operation will be described. Each control train comprises a normally depending crank 29 (Fig. 1) fulcrumed on the inner side frame of the machine. Pivotally connected at its lower end with crank 29 is a link 23 which at its upper end has a slot 23' engaged by a pin 25 which pivotally connects lever 19 and arm 21 of the associated locator. When the parts are in normal position (Fig. 1), pin 25 engages the lower end of slot 23' and locates link 23 so that it is in dead center relation with crank 29. A spring 27 biases link 23 toward the right and to a much lesser degree upwardly. The force of the spring 27, therefore, tends to rotate crank 29 counterclockwise, and through link 23 and arm 21, to raise the forward edge of carriage 1. The force of spring 27, however, is not great enough to overcome the force of spring urged lever 19 or the weight of the carriage alone. The carriage, therefore, is normally maintained in its lowered position by gravity and by the urge of the locators.

When the forward edge of carriage 1 is moved up-

wardly in a shifting operation, arm 21 of the locator will be moved upwardly therewith, thereby rocking lever 19 counterclockwise against the tension of its spring. Although link 23 and crank 29 are at dead center position, the start of this movement is allowed by slot 23' which permits upward movement of pin 25. However, as soon as pin 25 is moved from engagement with the bottom of slot 23', spring 27 will be permitted to rock link 23 counterclockwise about pin 25 and thereby rock crank 29 also counterclockwise to raise link 23 and reengage the bottom of slot 23' with pin 25. As the forward edge of the carriage completes its upward movement, the bottom of slot 23' will remain engaged with pin 25 as link 23 and crank 29 are rocked by spring 27 to the position shown in Fig. 3.

As crank 13 passes through its 90° position and the forward edge of carriage 1 starts to move downwardly, locator arm 21 will also be moved downwardly with the carriage by spring urged lever 19. Therefore, pin 25 connecting lever 19 and arm 21 will, by engagement with the bottom of slot 23', move link 23 downwardly and crank 29 clockwise from the position shown in Fig. 3. From an inspection of Fig. 3, it will be seen that, at the beginning of this movement, there will be little or no opposition thereto by spring 27 for the reason that, at this time, clockwise movement of crank 29 will lower its pivotal connection with link 23 quite rapidly but will move the connection very slowly toward the left to thereby tension spring 27. Furthermore, it will be seen that spring 27 at this time has substantially no tendency to move link 23 upwardly. However, as the forward edge of carriage 1 approaches its normal lowered position, a given downward speed of movement of link 23 will rotate crank 29 at an accelerated rate of speed for the reason that its pivotal point of connection with link 23 must move more rapidly to the left toward its dead center position to permit a given downward movement of arm 23. At this time, therefore, spring 27 will be rapidly tensioned, thereby tending to prevent the above-described acceleration of the clockwise movement of crank 29. Therefore, as the forward edge of carriage 1 is moved to its lowermost position, such rate of movement will be appreciably checked, and the parts will be brought to rest with link 23 and crank 29 in dead center position. It will be noted that lever 19 of the locator is not provided with a fixed stop as disclosed in the aforesigned patent. Such a stop is unnecessary for the reason that lever 19 and its connected arm 21 are brought to rest in their proper positions by pin 25 in engagement with the lower end of slot 23'. It will be seen, therefore, that noise which would normally result at the termination of a carriage shifting operation is substantially reduced by eliminating a fixed stop for lever 19 and by preventing acceleration of the carriage during the latter portion of its movement as it is lowered to normal position.

It has been found that normally the aforesigned

carriage shifting and cushioning means operates satisfactorily without application of spring power to locator levers 19, and that spring power is applied only to assure operation in the event of binds etc. in the mechanism.

5 If the mechanism is operated without spring power applied to levers 19, the rear arms of the levers act only as guide supports for pins 25 connecting arms 21 and links 23. When the mechanism is so operated, arms 21 are moved downwardly by the lower edge of rail 17 engaging the lower faces of the jaws of said arms as the carriage is moved downwardly by gravity. Otherwise, the operation is the same as hereinbefore described. Furthermore, it will be apparent that certain changes may be made in the shapes and arrangement of the parts without 10 departing from the principles of operation, and that the tension of springs 27 may be regulated in accordance with the weight and inertia of the parts and degree of cushioning desired. It will be understood, therefore, that the invention is to be limited only insofar as necessitated by the scope of the appended claims.

15 I claim:

1. In a calculating machine having a carriage pivotally and slidably mounted on the fixed frame of the machine, and means for denominational shifting said carriage including means for raising said carriage pivotally and then permitting said carriage to be restored downwardly by gravity; means for controlling the downward movement of said carriage, comprising a crank mounted on the fixed frame of the machine, a linkage connecting said crank with said carriage and operable to rotate said crank toward a horizontal position upon raising of said carriage and to restore said crank toward a vertical position upon downward movement of said carriage, and spring means for biasing said crank toward horizontal 20 position.

2. In a calculating machine having a carriage pivotally and slidably mounted at its rear on the fixed frame of the machine, means for denominational shifting said carriage including means for raising said carriage pivotally and then permitting said carriage to be restored downwardly by gravity, and a carriage locator comprising a spring urged lever mounted on the fixed frame of the machine and an arm having pivotal connection at one end with one arm of said lever and sliding connection at 25 its other end with the front of said carriage; means for controlling the downward movement of said carriage, comprising a crank mounted on the fixed frame of the machine, a link connecting said crank with said one end of said arm, and spring means for biasing said crank in opposition to said spring urged lever.
